UNITED STATES PATENT OFFICE.

ZINGEL C. BIRNBERG, OF YOUNGSTOWN, OHIO.

GAME COUNTER.

Application filed May 4, 1925. Serial No. 27,966.

To all whom it may concern:

Be it known that I, ZINGEL C. BIRNBERG, a citizen of the United States, residing at Youngstown, in the county of Mahoning and State of Ohio, have invented certain new and useful Improvements in Game Counters, of which the following is a specification.

This invention relates to counter or chip holding devices especially adapted for use in connection with various games involving the use of disk or other shaped counters or chips.

Briefly stated, an important object of this invention is to provide a counter holding device having a series of separate spaced vertically arranged pegs upon which the counters of different denominations may be mounted to provide a simple storing, carrying and computing means for the chips.

A further and equally important object of this invention is to provide a counter or chip carrier having a pair of closure sections which when closed will effectively contain the chips and when open will form a wide supporting surface and shallow receptacles for loose chips.

A further object of the invention is to provide a counter holder of the character specified which is of highly simplified construction, neat in appearance, and cheap to manufacture.

Other objects and advantages will be apparent during the course of the following description.

In the accompanying drawing forming a part of this application and in which like numerals are employed to designate like parts throughout the same,

40 Figure 1 is a perspective of the improved counter holder closed;

Fig. 2 is an end elevation of the counter holder open;

Fig. 3 is a fragmentary group perspective of the improved holder;

Fig. 4 is a perspective illustrating one form of counter or chip especially adapted for use in connection with the invention;

Fig. 5 is a plan view of the improved holder.

In the drawing, wherein for the purpose of illustration is shown a preferred embodiment of the invention, the numeral 5 generally designates the improved holder comprising a pair of similarly constructed

metal, celluloid, bakelite, ivory, or the like, and which as shown in Fig. 3 are provided with side and end flanges or walls 7 and 8, respectively.

The end walls 8 are provided with gear segments 10, which mesh with each other and which, therefore, assure the simultaneous opening and closing of the sections. Each end flange 8 is provided with an opening 12 at the axis of the gear segment 10 and this opening 12 is adapted for the reception of a pivot pin 14, by means of which the gear segment is connected to a flange 16 at the end of a rack 18.

It will be seen that the end walls 8 are geared to each other and are pivotally connected to the flanges 16 at the ends of the rack 18 so that the sections 6 may be moved to closed position as shown in Fig. 1 or to open position as shown in Figs. 2 and 5.

The flat rack 18 which might be said to form the bottom wall of the holder is provided with a plurality of spaced parallel pegs or posts 24 upon which suitable counters 26 of various denominations are mounted. At this point it might be stated that the counters 26 are preferably of annular formation although they may be of any formation and suitable means may be mounted on the rack 18 to hold the counters in place. Fig. 5 illustrates that the counters may be of various denominations and the different counters may be separated to expedite settlement, etc.

Also, when the sections 6 are in open position they form shallow receptacles for the loose counters. When the sections 6 are moved to closed position the notches 28 in the side walls 7 receive the pegs 24 and, therefore, hold the counters on the pegs and against loss. Also, the pegs 24 are braced at the upper ends thereof by the side walls 7 when the sections 6 are moved to closed position.

In carrying out the invention a suitable lock or spring clip 34 may be employed to hold the sections 6 in closed position. This clip may be of any style and may be secured on the holder at any place found practical.

It is important to note that the counters or chips cannot easily get out of place as the holder has no side motion and during the opening or closing of the holder the pegs 24 are positioned vertically. As the pegs 24 project above the holder when the holder is closed, it may be readily seen at a

glance just how the holder should be opened to avoid displacement of the chips.

A holder constructed in accordance with this invention is especially adapted for use in connection with a variety of games such as Mah Jongg, pinochle, poker, and the like.

Having thus described the invention, what is claimed is:

1. A counter holder comprising a rack having a plurality of counter holding pegs, the ends of the rack being provided with flanges, closure sections having end walls provided with integral gear segments meshing with each other, means pivotally connecting the end walls to said flanges, said sections being adapted to be positioned on opposite sides of said rack and being provided with locking means.

2. A counter holder comprising a rack having a plurality of spaced parallel counter holding pegs, the ends of the rack being provided with flanges, elongated sections having end walls provided with gear segments meshing with each other to assure simultaneous movement of the sections, means pivotally connecting the end walls to said rack, said sections being provided with side walls adapted to be positioned in edge to edge relation and being provided with notches to receive the upper portions of said pegs whereby to hold the counters mounted on the pegs against displacement when the holder is closed.

3. A counter holder comprising a rack having a plurality of spaced parallel coun-

ter holding pegs, the ends of the rack being provided with flanges, elongated sections having end walls provided with gear segments meshing with each other to assure simultaneous movement of the sections, means pivotally connecting the end walls to said rack, said sections being provided with side walls adapted to be positioned in edge to edge relation and being provided with notches to receive the upper portions of said pegs whereby to hold the counters mounted on the pegs against displacement when the holder is closed, said sections defining shallow receptacles when the holder is open.

4. A counter holder comprising a rack having a plurality of spaced parallel counter holding pegs, the ends of the rack being provided with flanges, elongated sections having end walls provided with gear segments meshing with each other to assure simultaneous movement of the sections, means pivotally connecting the end walls to said rack, said sections being provided with side walls adapted to be positioned in edge to edge relation and being provided with notches to receive the upper portions of said pegs whereby to hold the counters mounted on the pegs against displacement when the holder is closed, said sections defining shallow receptacles when the holder is open, and a lock for connecting the sections, said pegs being extended above the side walls of said sections.

In testimony whereof I affix my signature,

ZINGEL C. BIRNBERG.
